DESIGN FOR A DOLL

Caroline G. Davis, New York, N. Y.

Application May 20, 1944, Serial No. 113,703

Term of patent 7 years

(Cl. D34—4)

To all whom it may concern:

Be it known that I, Caroline G. Davis, a citizen of the United States, residing in New York, county and State of New York, have invented a new, original, and ornamental Design for a Doll, of which the following is a specification, reference being had to the accompanying drawing forming part thereof.

I claim:

The ornamental design for a doll, as shown.

CAROLINE G. DAVIS.
